DESIGN FOR A DRAFTSMAN'S TEMPLET

John R. Cambron, Dayton, Ohio

Application November 23, 1945, Serial No. 124,020

Term of patent 7 years

(Cl. D52--1)

To all whom it may concern:

Be it known that I, John R. Cambron, a citizen of the United States, residing at Dayton, in the county of Montgomery and State of Ohio, have invented a new, original, and ornamental Design for a Draftsman's Templet, of which the following is a specification, reference being had to the accompanying drawing, forming a part thereof.

In the drawings:

I claim:

The ornamental design for a draftsman's templet, as shown.

JOHN R. CAMBRON.
